UNITED STATES PATENT OFFICE.

JOHN M. FEDDERS, OF BUFFALO, NEW YORK, ASSIGNOR TO FEDDERS MANUFACTURING COMPANY, INC., OF BUFFALO, NEW YORK, A CORPORATION OF NEW YORK.

RADIATOR UNIT.

1,299,158.

Specification of Letters Patent.

Patented Apr. 1, 1919.

Application filed April 20, 1918. Serial No. 229,668.

To all whom it may concern:

Be it known that I, JOHN M. FEDDERS, a citizen of the United States, residing at Buffalo, in the county of Erie and State of New York, have invented new and useful Improvements in Radiator Units, of which the following is a specification.

This invention relates to radiator units which are more particularly designed for manufacturing the cores of radiators employed for cooling the water of automobile gas engines and the like, and more particularly to a radiator unit in which the body is constructed of substantially tubular form so that a current of air may pass through the same, a radiating device being arranged within the body for increasing the rapidity of the dissipation of the heat of the water to the air.

The object of this invention is to provide an improved radiating device for the interior of such tubular bodies and one which can be produced at low cost, is capable of being easily assembled and not liable to get out of order when in use.

In the accompanying drawings:

Figure 1 is a front elevation, partly in section, of a radiator core made up of units constructed in accordance with my invention. Fig. 2 is a vertical section of the same taken on line 2—2, Fig. 1. Figs. 3, 4 and 5 are perspective views of the several parts of one of the radiating devices contained within one of the tubular bodies of a unit.

Similar characters of reference indicate corresponding parts throughout the several views.

In its general organization, the core of the radiator which is adapted to receive my invention comprises a plurality of tubes which are preferably constructed of sheet metal and which are arranged side by side so that the interiors of these tubes form air passages 1 and the spaces between adjacent tubes form water channels or conduits 2. These tubes may be of various forms in cross section and in the instance herein shown the same are of hexagonal form. Each of these tubes is also preferably provided at its opposite ends with enlargements 3, 3, while the intermediate part 4 thereof is constructed of reduced diameter. When assembled, each of these tubes bears with the facets on its enlarged ends against corresponding facets of adjacent tubes of the core so as to

form closures for the water conduits on opposite sides of the radiator core.

One of my improved radiating devices is arranged within each of the air tubes, and in its preferred form is constructed as follows:

5 represents a diametrical radiating member which is constructed of sheet metal and extends diametrically across the space within a tube preferably from end to end thereof and engages its opposite longitudinal edges 60 with the bore of this tube. Midway of its width this diametrical radiating member is provided with a longitudinal bead 6 which is stamped from the stock of which this member is formed, so that this bead is of 70 concavo-convex form.

On opposite sides of this diametrical radiating member are arranged two substantially V-shaped radiating members each of which is also constructed from a single sheet 75 of metal. One of these members has its flanges 7, 7 connected at their inner longitudinal edges so as to form a salient inwardly-projecting corner or angle 8 which engages with the concave side of the bead 6 while the 80 outer disconnected longitudinal edges of these flanges engage with the inner side of the tubular body. The flanges 9, 9, of the other V-shaped member are connected at their inner longitudinal edges which latter 85 form an outwardly-receding seat 10 engaging with the convex side of the bead 6 while the outer longitudinal edges of these flanges engage with the bore of the tubular body.

Endwise displacement of the several radiating members within the respective radiating tubes is prevented by constructing the central parts of these members sufficiently narrow to engage with the contracted central part of the tubular body. At opposite 95 ends of their longitudinal edges the flanges of the radiating members are provided with laterally-projecting lugs or extensions 11 which engage with the enlargements at opposite ends of the body.

The several tubes are connected with each other at their opposite ends by mean of solder and the several parts of each radiating device are also preferably connected at opposite ends with each other and with the 105 companion tubes by means of solder.

Each of the radiating members has its outer longitudinal edge portions preferably bent so that the same is of spiral form in a direction lengthwise of the tube so as to 110

cause the air upon passing through the tube to be deflected upon engaging these members, thereby increasing the amount of heat which is taken up by the air and promoting the radiating efficiency of the core.

In the preferred form the front ends of the outer longitudinal edges of the several radiating members engage with the inner sides of the corners of the air tube so as to 10 preserve the symmetrical appearance of the structure while the rear parts of the longitudinal edges of these members are twisted circumferentially in the same direction, so that together they form a plurality of spiral 15 surfaces against which the air engages in passing through the radiator.

The various elements of this radiating device can be produced very rapidly at low cost by employing simple machinery and 20 comparatively unskilled labor and the same can also be assembled without difficulty and without liability of disarranging the parts, thereby producing an efficient radiator with considerable economy.

25 I claim as my invention:

1. A radiator unit comprising a tubular body, and a radiating device arranged within said body and comprising a diametrical member extending diametrically across the 30 space within said body and provided midway of its width with a longitudinal bead of concavo-convex form, and two V-shaped

members arranged on opposite sides of said diametrical member, one of which has the outer side of the angle between the inner connected inner edges of its flanges constructed of salient form and engaging with the concave side of said bead, and the other having the outer side of the angle between the inner connected inner edges of its flanges constructed in the form of an outwardly receding seat and engaging with the convex side of said bead.

2. A radiator unit comprising a tubular body, and a radiating device arranged within said body and comprising a diametrical member extending diametrically across the space within said body and provided midway of its width with a longitudinal bead of concavo-convex form, and two V-shaped 45 members arranged on opposite sides of said diametrical member, one of which has the outer side of the angle between the inner connected inner edges of its flanges constructed of salient form and engaging with the concave side of said bead; and the other having the outer side of the angle between the inner connected inner edges of its flanges constructed in the form of an outwardly receding seat and engaging with the convex 50 side of said bead and the outer edges of the flanges of both V-shaped members engaging with the bore of said body.

JOHN M. FEDDERS.
